TELEVISION RECEIVER SCREEN AND
SIMILAR SYSTEMS

Pierre Marie Gabriel Toulon, Neuilly-sur-Seine, France, assignor to Products & Licensing Corporation, New York, N. Y., a corporation of Delaware

Application July 25, 1947, Serial No. 763,664
In France April 1, 1943

Section 1, Public Law 690, August 8, 1946
Patent expires April 1, 1963

8 Claims. (Cl. 315—21)

1

The present invention relates generally to systems in which the luminous intensity of each of a plurality of elements of a surface is varied in accordance with amplitude variations of an electrical signal, and finds particular, though not exclusive, application in television receiver screens.

It is a broad object of the present invention to provide a novel system for varying the luminous intensity of the elements of a surface in accordance with variations of amplitude of an electrical signal.

It is a further object of the invention to provide as elements of a visible surface a plurality of fluorescent sub-areas which may be individually excited in controllable degree in response to electrical signals.

It is a further object of the invention to provide means for controllably determining the luminous intensity of each of a plurality of fluorescent elements of a surface by means of gas discharges to the elements of the surface, for time periods which are variable in response to the amplitude of a signal.

It is another object of the invention to provide a novel gaseous conduction device in which ionized gaseous plasma is continually generated, the plasma being effectively a cathode for a large number of anodes and control electrodes, and wherein the anodes are fluorescent in response to discharge from the plasma to the anodes in response to signals applied to the control electrodes.

It is still another object of the invention to provide a closed vessel wherein is located a plurality of fluorescent elements disposed side by side to form a composite surface therein, and wherein flow of ions to the separate fluorescent elements, from an ionized atmosphere provided within the vessel, is controlled in response to control signals.

The above and still further objects, features and advantages of the present invention will become apparent upon consideration of the following detailed description of a specific embodiment thereof, especially when taken in conjunction with the accompanying drawings wherein:

Figure 1 is a view taken in vertical section of a television receiver screen and associated control elements, arranged in accordance with the present invention;

Figure 2 provides graph of current flow during predetermined time intervals, as established in response to control signals, and further illus-

2

trates luminous intensity accomplished in response to each of the signals; and

Figure 3 is a schematic view corresponding with the structure of Figure 1, and illustrating in conventionalized manner the circuit elements and structure of the electronic tube of Figure 1.

Identical components in Figures 1 and 3 are identified by the same numerals of reference. There is provided an enclosed bulb 1, within 10 which is located a block fabricated of refractory material which separates bulb 1 into two independent compartments 3 and 4, electrically isolated from one another, in a manner which will become evident as the description proceeds. 15 In the compartment 3 is provided a cathode 5 and a cooperating anode 9, the anode 9 being supplied with voltage, through a resistance 10, by a source of positive anode potential 11, conventionally illustrated as a battery, this potential 20 being sufficiently high so that gas which is contained within the compartment 3 is maintained in ionized condition throughout the compartment 3.

In the compartment 4 is provided a cathode 25 6, which is maintained energized by a suitable source of potential, and an anode 12, which is maintained at a normal negative potential with respect to the cathode 6. There is applied to the anode 12 a positively going saw-tooth voltage 30 from a source 26. There is further provided a control electrode 13 between the cathode 6 and the anode 12, a source of modulation or control signal in the form of a voltage wave being applied between the cathode 6 and the control electrode 13 via terminals M for the purpose of 35 controlling ionization of the gas contained in the compartment 4.

Ionization of gas contained in the compartment 3 is prevented from spreading beyond the chamber 3 by means of grids 7, which are supplied with suitable negative voltage from source 14 through protective resistance 15. Similarly 40 ionization of gas contained in the compartment 4 is prevented from spreading beyond the compartment 4 by means of grids 8, which are similarly connected via protective resistance 16 to a source of negative potential 17. The grids 7 and 8 accordingly operate to isolate the chambers 3 and 4, respectively, from one another in respect to 45 spread of ionization, so that gas in one of the chambers may be ionized when the gas in the other chamber is not ionized, and so that the intensity of the ionization in either of the chambers will not be reflected as a change in ionization 50 in the other chamber.

A visible screen is provided in compartment 3, which is constituted of a multiplicity of elementary anodes 17, 17', 17'', etc. Each of the anode elements is covered with fluorescent material, so as to become highly luminous under the impact of ions striking it, these ions deriving from the ionized gaseous plasma contained in compartment 3.

It will be clear from the preceding description that in each of compartments 3 and 4 is formed a virtual ionic cathode, in the form of ionized gaseous plasma, which acts with respect to the anodes in the compartments, much as does a conventional heated cathode. It will be heated, however, that in compartment 3, since no control electrode is provided, and since a constant voltage exists between anode 9 and cathode 5, that a constant ionization of the gas contained in compartment 3 is maintained. Therefore, with respect to anode 17, 17', 17'' the gaseous plasma provides essentially a cathode of constant emissive power, which is available for any one of the anodes at any time.

In chamber 4, on the other hand, this is not true, since anode 12 is supplied with saw-tooth voltage from a saw-tooth voltage generator 26, and since a control electrode 13 is provided, which is subjected to signal voltages of variable amplitude, applied to terminals M.

Considering first the operation which takes place in compartment 4, it will be evident that the anode 12 rises positively in voltage with respect to the cathode 6 at a constant rate, and that for any given voltage applied to the control electrode 13 ionization will take place only after the anode 12 has reached some predetermined positive value, and once it has taken place will continue until anode potential is reduced to zero. The positive value of anode voltage at which ionization initiates in turn depends upon the magnitude of the control voltage applied to control electrode 13. Accordingly, for each cycle of saw-tooth voltage provided by saw-tooth generator 26 ionization takes place in chamber 4 for a period of time which is determined by the magnitude of the signal applied to control electrode 13, and for the remaining time the gas contained in chamber 14 is deionized.

Reference is now made to Figure 2 of the accompanying drawings, for a further explanation of the phenomena explained in the previous paragraph.

Figure 2 shows saw-tooth voltages 31, 31', 31'', as supplied by saw-tooth voltage generator 26. Voltages 32, 32' and 32'' represent signal amplitude supplied to the control electrode 13. It will be noted that the signal 32, which is relatively small in amplitude, permits ionization of the gas in compartment 4 when the anode voltage 12 has reached a relatively small positive value as at 33. The intermediate signal value 32' delays ionization until the saw-tooth voltage 31' has attained a magnitude 33'. On the other hand, the still greater signal amplitude 32'' delays ionization until the saw-tooth voltage 31'' has attained a value 33''. Accordingly, the total duration of ionization in the compartment 4, for each saw-tooth cycle, is a function of the signal amplitude existing, during the saw-tooth cycle, on the control electrode 13, but the magnitude of ionization, as is well understood, is of constant amount. The effect of the signal voltage applied to control electrode 13 via terminals M is, then, to establish in the compartment 4 a series of pulses of ionization, which are of constant amplitude, but of

variable duration, and by virtue of such variable durations represent the signal applied to the terminals M. The total durations of these ionization pulses is represented in Figure 2 by the shaded areas 34, 34', and 34'' respectively in response to control voltage amplitudes 32, 32' and 32''.

There is provided in the compartment 4 a plurality of anodes 25, 25', 25'' etc., with respect to which the gaseous ionized plasma in the compartment 4 forms a cathode, and particularly a cathode which is active and inactive in alternation, the active periods being of variable duration in accordance with the amplitude of the input signal at the terminals M. Applied to the anodes 25, 25', and 25'' is a series of positive pulses, which derive from the source 24 in Figure 1, represented in Figure 3 as 124, these pulses being applied to the anodes 25, 25', 25'' via condensers 23, 23', 23'', respectively, in time sequence. Voltage peaks are all of the same amplitude, and follow each other at equal intervals of time, so that the anodes 25, 25', 25'' are energized in sequence for predetermined times. Current accordingly flows from the gaseous plasma in the compartment 4 to the anodes 25, 25', 25'' in sequence, but only for the times when the plasma is ionized, since at other times no cathode exists from which the anodes 25, 25', 25'' may draw current. Accordingly, current flows in the separate anode circuits 122, 122', 122'' (Figure 3) only when these anodes are supplied with positive voltage from the source 124, which occurs in sequence, and during each anode energization only for the time during which the gaseous plasma is energized, and consequently for a time which is inversely proportional to the amplitude of the impressed signal at the terminals M.

Current flow from the anodes 25, 25', 25'' to cathode 6 takes place from condensers 36, 36', 36'' via resistors 22, 22', 22'', since these condensers tend to assume the voltages of the associated anodes 25, 25', 25'' respectively, and accordingly, these condensers become discharged to a voltage which is proportional to the durations of the separate pulses of ionization in the compartment 4. The voltage on the condensers 36, 36', 36'' respectively are inversely proportional, then, to the amplitudes of the signals occurring during the times when the condensers are being discharged.

The condensers 36, 36', 36'' are connected directly to control electrodes 21, 21', 21'', which are respectively associated with anodes 17, 17', 17'', all of which have for their cathode the continuously ionized gaseous plasma in the compartment 3, and all of which are normally at the potential of cathode 5.

There is applied to the anodes 17, 17', 17'' from a source of saw-tooth voltage 20, in parallel, a positively going saw-tooth voltage which tends to effect a discharge from the ionized plasma to the anode respectively. The discharge, however, can take place only at times in the positive saw-tooth voltage cycle which is determined by the potential on the control electrodes 21, 21', 21''. These latter are sequentially at a potential positive relative to their unmodulated value by an amount inversely proportional to the signal input applied to the terminals M. At the same time the total period of discharge of condensers 36, 36', 36'' to the anodes 17, 17', 17'' is inversely proportional to the signals on the control electrodes 21, 21', 21'', as will be evident from Figure 2 of the drawings. From this figure, it will be

evident that a larger input signal permits transfer of current to an anode 25, 25', 25'' during a shorter interval of time. Accordingly, the total time during which current flow occurs with respect to any of anodes 17, 17', 17'' becomes directly proportional to the amplitude of the signal applied to the input terminals M. The total illumination produced on any one of the anodes 17, 17', 17'', by reason of bombardment of the fluorescent coating thereof by the ionized gas, is a function of the total time during which the bombardment takes place, and, accordingly, an observer of the fluorescent anodes 17, 17', 17'', will perceive at each of these elements an intensity of illumination which is proportional to the amplitude of the signal applied by the terminals M, during the time when the element is in circuit in response to voltages supplied by the commutation voltage source 124.

In order to effect re-charge of the condensers 36, 36', 36'' to the proper negative values in the intervals intervening between signal application thereto, so that each condenser may be ready for a succeeding discharge, representative of a succeeding portion of the input signal, resort is had to a system of the character of that described in my U. S. Patent application Serial #739,153, entitled "System for Controlling the Flow of Successive Electrical Impulses in a Channel," filed April 3, 1947, and issued February 13, 1951 as Patent No. 2,541,138. Essentially, this application discloses a device which provides a series of identical voltages having successive constant phase difference with respect to one another, the voltages having rectangular wave shapes, as shown at 129 in Figure 3, and the voltages deriving from a source 29, and being applied to the condensers 36, 36', 36'', in succession, synchronization between the source 124 and the source 29 being such that each condenser is raised in potential in response to a voltage provided by the source 124, and then lowered in potential in response to a voltage provided by the source 129, the total time period between raising and lowering being that established by one cycle of saw-tooth voltage as provided by saw-tooth source 26. Once any condenser has been lowered in potential to its normal value, it is so maintained by potential source 30.

The elements 37, illustrated in Figure 3 of the drawings, represent capacitors, which may be utilized to transfer voltages from the sources 124 and 129 through the glass envelope of the tube 1.

Briefly described, then, and in accordance with the present invention, a signal is applied to the terminals M, establishing a variable voltage on the control electrode 13. The anode 12 is raised from a negative potential, or from a zero potential if desired, in a positive direction in response to saw-tooth voltage provided by the saw-tooth generator 26. When the saw-tooth voltage attains a value determined by the then instantaneous value of the signal applied to control electrode 13, the gas in compartment 4 ionizes. Accordingly, ionization takes place in the form of pulses having durations established by the amplitude of the input signal at the terminals M. Positive voltages are applied from source 124 to the anodes 25, 25', 25'', in sequence, and in synchronism with the saw-tooth voltage provided by the source 26. During the time that any one of anodes 25, 25', 25'' is selectively positively polarized in response to voltage from the source 124, and the gas in compartment 4 is simultaneously ionized in response to voltage applied to the

anode 12 and the control electrode 13, current flows to the anode 25 and to the selected ones of the anodes 25, 25', 25'', which then attains a voltage approximately that of the cathode 6.

5 Condensers 36, 36', 36'' are normally maintained at a fixed negative potential by a potential source 30, and maintain control electrodes 21, 21', 21'', respectively, at the same negative potentials. There is applied to anodes 17, 17', 17'', associated respectively with control electrodes 21, 21', 21'', a saw-tooth voltage from a source 28, this voltage being positive going, and consequently capable of establishing flow of current between the anodes and ionized gaseous plasma in the compartment 3, should the relation between the voltages on any given anode and control electrode be suitable for this purpose. Normally the negative bias on the control electrodes 21, 21', 21'', is sufficiently high to prevent such action. However, when any one of anodes 25, 25', 25'' discharges through the ionized gaseous plasma in compartment 4, voltage on the corresponding one of condensers 36, 36', 36'' is raised in a positive direction, so that effectively negative bias is removed from the corresponding control electrodes 21, 21', 21''. The total discharge which takes place from the selected condenser is determined by the total period during which ionization occurs in compartment 4, since the discharge of the condenser takes place through an associated resistor, as 22, 22', 22'', only during such time. Accordingly, the selected condenser, of condensers 36, 36', 36'', eventually attains a potential more positive than its normal potential, and which represents the total time of ionization of the gas in compartment 4 during one cycle of saw-tooth voltage supplied by source 26, and consequently also represents the intensity of the signal applied to input terminals M. When 30 a selected control electrode 21, 21', 21'' attains a more positive potential than is normal, current flow from the ionized plasma in compartment 3, to a corresponding anode, may take place at a suitable time during a cycle of saw-tooth voltage from the source 28. Accordingly, these current flows take place for periods representative of the amplitude of the signal applied to terminals M. The effect on the observer of any one of fluorescent anodes 17, 17', 17'' is to average out 35 the total illumination on the anode, and accordingly the effect of illumination of the anode represents the amplitude of the input signal at terminals M.

55 While I have described and illustrated one specific embodiment of my invention, it will be evident to those skilled in the art that various modifications thereof may be resorted to without departing from the true spirit and scope of the invention.

60 What I claim is:

1. In combination, an electronic tube having an envelope containing gas, a heated cathode and an anode in said envelope, means for maintaining a positive potential between said anode and said cathode of sufficient magnitude to maintain said gas ionized, a plurality of further fluorescent anodes immersed in said gas, a separate control electrode adjacent each of said anodes, means biasing said electrodes normally to prevent current flow to said anode from said ionized gas, a source of positive saw-tooth voltage, means for applying said saw-tooth voltage to said plurality of fluorescent anodes, current flowing to each of said anodes during said voltage upon at-

tainment of a value of said voltage determined by the bias of the adjacent control electrode.

2. A system comprising, a closed vessel, a plurality of fluorescent anodes disposed in said vessel to form substantially a composite fluorescent surface therein, a gaseous atmosphere in said vessel, means ionizing said gaseous atmosphere, means for sequentially establishing a flow of gaseous ions from the ionized gaseous atmosphere to said fluorescent anodes in succession, a source of control signal, and means responsive to said control signal for controlling the duration of the flow of gaseous ions from the ionized gaseous atmosphere to each of said anodes in accordance with the amplitude of said control signal.

3. The system in accordance with claim 2 wherein said means responsive to said control signal includes a control electrode associated with each of said anodes, and means for applying said control signal to said control grids in sequence.

4. A system comprising a closed vessel, a gaseous atmosphere in said closed vessel, means for establishing ionization in said gaseous atmosphere along a predetermined path in said gaseous atmosphere, and a plurality of fluorescent anodes disposed in a path parallel to but displaced from said predetermined path, a separate control electrode interposed between said predetermined path and each of said anodes, and means for applying operating potentials to said control electrodes and to said anodes.

5. The combination in accordance with claim 4 wherein a saw-tooth voltage is commonly applied to all said anodes, and wherein positively going control signal is applied to said control electrodes in sequence, and means normally biasing all said control electrodes to cut-off.

6. An electronic system for receiving electric

signals and translating said signal into a visual representation, comprising, a plurality of conducting fluorescent elements disposed side by side to constitute a composite surface inside said bulb, means for forming an ionized atmosphere adjacent said composite surface, means for generating a periodic saw-tooth voltage, means for applying said saw-tooth voltage simultaneously in positive polarity to all said elements simultaneously, a separate control grid interposed between each of said elements and said ionized atmosphere, a plurality of normally blocked signal transmitting channels having each an output circuit, means connecting a separate one of said output circuits to each of said control electrodes, each of said channels comprising an input circuit, means for applying said electric signal to said input circuit, and a source of voltage for unblocking said channels in succession.

7. The combination in accordance with claim 6 wherein said source of voltage comprises means for generating sharp voltage pulses in said channels in sequence.

8. The combination in accordance with claim 7 wherein is further provided means reblocking said channels in sequence and with predetermined time delays following said sharp voltage pulses.
